LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

Application filed September 21, 1916. Serial No. 121,377.

My invention relates to railway signaling, and particularly to signaling of the type in which alternating current, preferably of high frequency is employed in the track rails for the purpose of controlling traffic thereover.

I will describe certain forms of signaling systems and apparatus embodying my invention, and will then point out the novel features thereof in claims.

In the accompanying drawing, Fig. 1 is a diagrammatic view showing one form of signaling system embodying my invention. Fig. 2 is a diagrammatic view showing a modified arrangement of the vehicle-carried receiving circuit shown in Fig. 1. Fig. 3 is a diagrammatic view showing one arrangement of speed governing apparatus which may be employed in conjunction with the relays shown on the vehicle in Figs. 1 and 2. Fig. 4 is a view similar to Fig. 1 but showing a modification thereof also embodying my invention. Fig. 5 is a view similar to Fig. 3 but showing an adaptation of the speed controlling apparatus to the system of Fig. 4. Fig. 6 is a view showing one form of apparatus for transforming a low frequency current into one of high frequency at or near the point at which the current is to be impressed upon the track rails. Fig. 7 is a diagrammatic view showing a further modified form of the signaling systems shown in Figs. 1 and 4.

Similar reference characters refer to similar parts in each of the several views.

Referring first to Fig. 1, the reference characters H and H' designate the track rails of a railway along which cars or trains normally move in the direction indicated by the arrow. The railway is divided into block sections A—B, B—C, etc., by any suitable means which, as here shown, are insulated joints 2 in the rail H'. The other rail H being electrically continuous it may, if the propulsion energy for the cars is electricity, be included in the circuit for the propulsion current in the usual or well known manner. It is immaterial to the present invention, however, how the segre-

gation of the block sections is accomplished, 50 and whether or not the car propulsion energy is electricity, and if so, whether it is direct or alternating current.

For each block section I provide means for impressing on the rails thereof alternating signaling currents differing in frequency. As here shown, two such currents are employed, and as shown in Fig. 1, they are supplied from two pairs of transmission mains 3 and 3^a, which pairs are connected respectively with two generators 4 and 4^a of high frequency currents differing in frequency. The frequencies of these currents may be, for example, 7,000 and 10,000 cycles per second, although it is understood that the frequency values may be radically different from those given as examples without departing from the scope of my invention. For each section I provide two transformers T and T', the primaries of which are connected respectively with transmission mains 3 and 3^a, and the secondaries of which are connected with the track rails of the section adjacent the exit end thereof. Connected in series with the primaries of each of the transformers T is a condenser 5 which serves to balance the reactance of the circuit and thus to reduce the impedance of the circuit to a minimum to currents of the frequency of generator 4, that is, the primary circuit of transformer T is tuned to resonance. Similarly, condenser 5^a is connected in series with the primary of transformer T' in order to reduce the impedance of this circuit to a minimum to currents of the frequency of generators 4^a. The secondary of each transformer T is connected directly across the rails, and connected in series with the secondary of each of these transformers is a condenser 6 which forms with the secondary winding a circuit resonant to the frequency of the current supplied to the primary of this transformer. The secondary of each transformer T' is also connected in series with the condenser 6^a to form a circuit resonant with the respective primary, the supply of current from each transformer T' to the rails of the corre-

sponding section being controlled by the condition of traffic in the section next in advance, as I will hereinafter explain.

Located adjacent the entrance end of each block section is a relay S adapted to respond to current of the frequency supplied to the rails by transformer T . This relay is connected in a circuit including the secondary of a step-up transformer 7 and a condenser 8 , which circuit is tuned to resonance at the frequency of the current delivered by transformer T . The primary of transformer 7 is connected across the track rails of the section and in series therewith is a condenser 9 , this condenser and the transformer primary forming a circuit tuned to resonance at the frequency of the current delivered by transformer T . It will be seen, therefore, that in any one block section the resonant circuit comprising condenser 6 and the resonant circuit comprising condenser 9 are coupled together by the rails of the section, so that if such section is unoccupied and the rails thereof are intact throughout, current of the frequency of generator 4 is supplied to transformer 7 and so to the relay S and this relay is therefore energized.

As stated hereinbefore, the supply of energy from each transformer T' to the rails of the corresponding section is controlled by traffic conditions in the section next in advance. As here shown, this is accomplished by a contact 10 of the relay S for the block in advance, which contact is closed only when relay is energized. It will be seen, therefore, that current from any transformer T' is supplied to the rails of the corresponding section only when the section next in advance is unoccupied and the rails thereof are intact.

In Fig. 1 I have shown adjacent the entrance end of each block section a second relay S' responsive to current of the frequency supplied by generator 4^a and transformer T' . This relay S' is necessary only in case fixed or roadside signals are desired; in the event that such signals are not provided, this relay can be dispensed with. Relay S' is connected with the track rails in the same manner as relay S , except that the circuit comprising condenser 8^a and the secondary of transformer 7^a , and the circuit comprising the primary of this transformer and condenser 9^a , are resonant to current of the frequency delivered by generator 4^a and transformer T' .

Inasmuch as relays S and S' are connected with the track rails through the medium of circuits resonant to the frequencies of transformers T and T' respectively, it is obvious that these relays will respond selectively to currents of these two frequencies, that is, neither relay will be energized unless current of the frequency to which its associated circuits are tuned is present.

In Fig. 1 I have shown fixed or roadside signals F , F' , etc., but the provision of such signals is not essential for the reason that the passage of cars or trains along the railway may be adequately governed by the signals and other apparatus on the cars or trains themselves, as hereinafter described and explained. One fixed signal device is located adjacent the entrance end of each block section, and as here shown, each of these signals is of the well known "light" type comprising three electric lamps G , Y and R , indicating, when illuminated, "proceed", "caution" and "stop," respectively. These several indications are usually conveyed by green, yellow and red glass in front of the respective lamps, as is well understood in the art. These lamps are controlled by relays S and S' through the medium of circuits supplied with current from a suitable source, such as a battery 11 . These circuits need not be traced in detail, it being sufficient to point out that lamp G is controlled by the upper point of contact 12 of relay S and the upper point of contact 13 of relay S' so that this lamp can be illuminated only when both relays are energized, that is, when the corresponding block section and the section next in advance are unoccupied; lamp Y is controlled by the upper point of contact 12 of relay S and the lower point of contact 13 of relay S' so that this lamp is illuminated only when relay S is energized and relay S' de-energized, that is, when the corresponding block section is unoccupied and the section next in advance is occupied; and lamp R is controlled only by the lower point of contact 12 of relay S so that this lamp is illuminated only when this relay is de-energized, that is, when the corresponding section is occupied by a car or train.

At the left of the drawing I have shown diagrammatically a railway vehicle V (a car, locomotive or train) which is equipped with apparatus adapted to be controlled by the signaling currents in the track rails and which apparatus is arranged to give signal indications by virtue of which the speed or progress of the vehicle are governed. As here shown, the signaling apparatus comprises three lamps, G' , Y' and R' , which lamps are used to give the same indications as those in the roadside signals, viz, "proceed", "caution" and "stop." The signal lamps on the vehicle are controlled by two relays P and P' also carried on the vehicle, and this control is exactly the same as the control of the lamps, in any one of the roadside signals by the corresponding roadside relays S and S' . The relays P and P' are responsive to the high frequency signaling currents, and are controlled by these currents in the manner which I will now explain.

5 Mounted on the vehicle V in front of the forward pair of wheels is a coil 14 which is in inductive relation to the forward axle and to a short section of both of the track rails in advance of that axle. Across the terminals of coil 14 is connected a condenser 15, coil 14 and condenser 15 comprising a closed circuit α tuned broadly to the mean of the two frequencies of generators 4 and 4^a.

10 Inasmuch as the currents which flow in this circuit are very feeble and are therefore unsuitable to operate relays constructed with sufficient ruggedness for commercial purposes, I interpose between the circuit and the 15 relays a current amplifying device K, which I will now describe.

The amplifying device K comprises a vacuum tube or bulb 16 having mounted therein a filament 17, preferably of tungsten, 20 a metallic plate 19, and a metallic grid 18 interposed between the filament and the plate. The filament 17 is constantly heated by a battery 20, and the terminals of coil 14 and condenser 15 are connected by wires 21 25 and 22 respectively with the grid 18 and one terminal of the filament 17 so that the alternating currents in the resonant circuit α produce an alternating difference of potential between the grid and the filament. A battery 23 is connected with the filament 17 and the plate 19 in such direction that a flow of current through the tube or bulb will result, owing to the electron emission from the heated filament 17. The oscillating difference in potential between the grid and the filament serves to increase and decrease the rate of emission of electrons from the filament and hence produces corresponding variations in the strength of current flowing in 40 the circuit of battery 23. The circuit of battery 23 includes the primaries of transformers 25 and 25^a across whose terminals is connected condenser 24 to tune the transformer circuit broadly to the mean of the 45 two frequencies of generators 4 and 4^a. The secondaries of these transformers are connected with relays P and P' respectively by means of circuits made resonant to the two signaling frequencies respectively by condensers 26 and 26^a, as shown. The variations 50 in the strength of the current from battery 23 are thus reproduced as alternations in the resonant relay circuits, the action of the amplifying device thus corresponding to 55 that of a relay.

The operation of the system shown in Fig. 1, so far as the fixed on a roadside signal E is concerned, will be readily understood and may be briefly explained as follows:

60 When a section such as D-E is occupied by a vehicle V', the red lamp R of the signal for that section is illuminated, because both relays S and S' for the section are deenergized; the signal therefore indicates stop.

65 As for the signal E for the section next in

the rear, the lamp Y is illuminated, thus indicating caution, because relay S' is deenergized, current from transformer T' for this section being cut off at contact 10 of relay S for section D-E; relay S for section 70 C-D, is however, energized because of the presence in the rails of this section of current from transformer T at the exit end of the section. The green lamp G of the signal for the second section in the rear (section 75 B-C) is illuminated because both relays S and S' for this section are energized; the signal E for this section, therefore, indicates "proceed."

The operation of the vehicle carried signaling apparatus is as follows:

When the vehicle V is in section A-B, which section is unoccupied except for vehicle V, both relays P and P' on this vehicle are energized so that the green lamp G' is 85 illuminated, indicating "proceed." As the vehicle enters section B-C, no change will occur because this section and the section C-D in advance are unoccupied. When, however, the vehicle enters section C-D, 90 which is the section in the rear of an occupied section, relay P' will become de-energized because the signaling current to which this relay responds is not present in the rails of the section; lamp G' will therefore be extinguished and lamp Y' will become illuminated so that the signal on the vehicle indicates "caution." As the vehicle V enters section D-E which is already occupied by vehicle V' in advance of V, relay P will also 100 become de-energized because of the absence of signaling current in the rails of this section, so that lamp Y' will become extinguished and lamp R' will be illuminated, indicating "stop."

In Fig. 2 I have shown an alternative means for transmitting energy from the track rails to the apparatus on the vehicle. Instead of employing a coil in inductive relation to the rails as in Fig. 1, the resonant circuit α' (corresponding to α in Fig. 1) is connected directly with the journal boxes or wheels of the front axle of the vehicle, the inductance of this axle and connecting wires 110 14 constituting the inductance of the resonant circuit α' which corresponds to resonant circuit α of Fig. 1. The operation of the vehicle-carried apparatus when this modification is employed is the same as that of the apparatus of Fig. 1.

115 It is, of course, understood that the relays P and P' on the vehicle may be employed to give signals of any desired character or to control the vehicle in any desired manner. If it is desirable to govern the speed of the vehicle in accordance with traffic conditions in advance, such control may be accomplished by means such as that shown in Fig. 125 3, wherein 27 is a contact arm operatively connected with the running gear of the vehicle.

hicle through the medium of a speed-responsive device Q so that the position of this arm varies with variations in the speed of the vehicle; the higher the speed, the farther this arm swings to the right, and vice versa. This arm co-operates with fixed contact segments 28, 29, and 30, which are included in circuits with the contacts of relays P and P'. A brake application magnet M is controlled by these circuits in the following manner. When both relays P and P' are energized, the circuit for magnet M is completed through the upper contact points of these relays and the fixed contact segment 28, which is of such length that the vehicle may proceed at maximum speed before the circuit will be opened by the movement of arm 27 beyond the right hand end of segment 28. When, however, relay P' becomes de-energized and relay P is energized, this being the caution condition of vehicle carried apparatus, the circuit for magnet M is completed through the lower contact point of relay P' and segment 29, which segment is shorter than segment 28, so that the vehicle must proceed at an intermediate speed in order to avoid opening the circuit of magnet M. When both relays P and P' are de-energized, this being the stop condition of the apparatus, the circuit for magnet M is completed through the very short segment 30, so that if the vehicle exceeds a very low speed, the circuit for magnet M will be opened and the brakes applied. It is understood that so long as magnet M is energized, the brake pipe remains closed and the brakes are not applied. The three speeds corresponding to segments 28, 29 and 30 may be any desired values, such, for example, as 60, 30 and 10 miles per hour.

Referring now to Fig. 4, the signaling system here shown is similar to that shown in Fig. 1 except as to the means for supplying the currents of the two signaling frequencies to the rails of each section. In this view, the two pairs of transmission means 3 and 3^a are alternately connected with the rails of the successive block sections through transformers T and T', so that the rails of any one block section are directly supplied with current of only one frequency. In order to secure currents of both frequencies in each block section, I provide resonant transformer bonds N and N^a connected around the rail joints 2, each bond comprising a transformer whose primary is connected with the two adjacent sections of rail H' and whose secondary is connected with a condenser as shown. Each of these bonds is adjusted to resonance at the frequency of the current which is directly supplied to the forward of the two sections to which the bond is connected; that is, bond N^a at location B is resonant to the frequency of generator 4, bond N at location C is

resonant to the frequency of generator 4, etc. It will be seen, therefore, that normally the current which is directly supplied to each section is freely transmitted to the section next in the rear, but cannot reach the second section in the rear because it is intercepted by a bond which offers a relatively high impedance to current of that frequency.

Relays S and S' are supplied with energy from the track rails exactly as in Fig. 1, the circuits for these relays being tuned as before, so that relay S responds only to current from a transformer T and relay S' only to current from transformer T'. It will be evident, therefore, that when a block section is occupied by a car or train, both relays connected with that section will be de-energized and only one relay for the section in the rear will be energized, depending on which frequency is directly supplied to such section in the rear. Because of this fact that one relay or the other may be energized to give a caution signal, the control of each signal E by the relays S and S' is slightly different from that shown in Fig. 1. This control is such that if both relays are energized (as shown at location B) the circuit for the green, or "proceed" lamp, G, is closed through the upper contact points of each relay; if both relays are de-energized (as shown at location D) the circuit for the red or "stop" lamp R is closed through the lower points of the contacts of both relays; whereas, if either relay is energized and the other de-energized, the circuit for the yellow or "caution" lamp is closed through an upper contact point of the energized relay and a lower contact point of the de-energized relay. It is believed that the operation of these signal circuits will be obvious from this explanation and that no further detailed description is required.

The apparatus on the vehicle V is exactly the same as that shown in Fig. 1, except that the control of the vehicle-carried signal lamps G', Y' and R' by relays P and P' is the same as that of each roadside signal F by the relays S and S'.

The operation of the system shown in Fig. 4 will be obvious from the foregoing description of the structure, and from the explanation given hereinbefore of the operation of the system shown in Fig. 1. It is apparent that when a section, as D-E, is occupied by a car or train, the red or "stop" lamp R of the signal for that section will be illuminated because both relays S and S' for such section are de-energized; the yellow or "caution" lamp Y of the signal for the section C-D next in the rear is illuminated because relays S for this section is energized and relay S' de-energized; the green or "proceed" lamp G of the signal for the second section in the rear (section B-C) is

is illuminated because both relays for this section are energized. As the following vehicle V enters section C—D, relay P' will become de-energized because the rails of this 5 section contain current from transformer T only, hence the green lamp G' will become extinguished and the yellow lamp Y' will become illuminated. As the vehicle proceeds into the already occupied section D—E 10 the other relay P will also become deenergized because of the absence of signaling current in the rails in the rear of vehicle V', so that the red lamp R' will become illuminated and the yellow lamp extinguished. 15 It is, of course, apparent that the circuit a on vehicle V might be connected directly with the journal boxes or wheels of the front axle on the vehicle as in Fig. 2, instead of receiving energy inductively from the rails 20 as in Fig. 4. If speed control is desired in connection with, or instead of, the signal lamps on the vehicle, it may be provided as 25 shown in Fig. 5, wherein the brake magnet M and the contact arm 27 and the fixed contacts with which it co-operates are the same as in Fig. 3. The operation of this apparatus is as follows:

When both relays P and P' are energized, the circuit for brake magnet M is completed 30 through the upper contact points of these relays and contact segment 28, so that the vehicle may proceed at maximum speed without a brake application being incurred. When, however, relay P' becomes de-energized, relay P remaining energized, the circuit for magnet M is closed through the upper point of contact 32 and lower point of contact 33 and segment 29, thus imposing an intermediate speed limit on the vehicle. If 40 the relay P becomes de-energized and relay P' remains energized, the circuit for magnet M is still completed through segment 29 but now passes through the upper point of relay contact 33^a and the lower point of contact 32; the intermediate speed limit is thus imposed on the vehicle. When both relays P and P' become de-energized, the circuit for brake magnet M is closed through segment 30, lower point of contact 33^a and lower 50 point of contact 32, so that a very low speed limit must be observed or a brake application will ensue.

While I have in Fig. 4 shown fixed or roadside signals F, F, etc., such signals may 55 be eliminated entirely if so desired, because the movements of the cars or trains can be safely and satisfactorily governed by the apparatus on such cars or trains alone. In the event of the elimination of these fixed 60 signals, the relay S and S' and their' connections with the track rails can, of course, also be eliminated, leaving no apparatus in the trackway other than the resonant bonds N and N^a and the transformers, etc., for 65 supplying signaling energy to the rails.

In lieu of generating the high frequency currents at a central point by generators 4 and 4^a, as shown in Figs. 1 and 4, the high frequency current may be generated by apparatus local to each block section, such as 70 is shown in Fig. 6, utilizing as a source of energy an alternating current transmission line 3^b of a usual commercial frequency.

In Fig. 6 I have shown means for transforming alternating current of a commercial 75 low frequency into one of high frequency, and for impressing the high frequency current upon the track rails for the purpose of actuating signals as hereinbefore described. I accomplish this transforming operation by 80 first rectifying the alternating current of low frequency and then utilizing the resulting direct current to excite a vacuum tube device connected to act as a generator of sustained oscillations, whose oscillating circuit is inductively coupled to the track rails. 85

To alternating current transmission line 3^b is connected the primary of transformer T₀ having three secondary windings T₂, T₃ 90 and T₄. T₃ is of low voltage, and is for the purpose of constantly energizing the filaments 34, 34, of the vacuum tube rectifiers R₁ and R₂. T₄ is likewise of low voltage 95 and is for the purpose of constantly energizing the filament 35 of the vacuum tube device R₃. T₂ is of high voltage and has its terminals connected to the plate terminals 36, 36, of the rectifiers R₁ and R₂, while the middle point of its winding is connected to 100 wire 37. A wire 38 is connected to one terminal of each of the filaments 34 of rectifiers R₁ and R₂.

When the filaments 34 are heated, a positive potential applied to plate 36 will cause 105 a flow of current from the plate to the filament due to the emission of electrons from the heated filament, while the tube offers a practically infinite resistance to the flow of current in the opposite direction. It will 110 be evident therefore that when the secondary T₂ is energized by the primary T₀ unidirectional flow of current through the tubes will result, one tube permitting the passage 115 of positive half waves, the other of negative half waves, thus rectifying the alternating current of the transmission line 3^b into direct current. This rectified current is conveyed to the vacuum tube device R³ by means of wires 37 and 38, a condenser 39 being 120 connected across the wires 37 and 38 for smoothing out the current as will be readily understood.

Wire 38 is connected to the plate 40 of R³ while wire 37 is connected to the filament 35. Interposed between the plate 40 and the filament 35 is a grid 41 which is connected by wire 42 to resonant circuit a², comprising condenser 43 and the secondary of transformer 44. The primary of transformer 44 130

- is in the direct current circuit formed by the conductors 37 and 38, plate 40 and filament 35 of R^3 . It will be evident, therefore, that oscillations in the resonant circuit 5 a^2 will produce an alternating difference of potential between grid 41 and filament 35, which will cause a corresponding variation in the direct current from wire 38 to plate 40, filament 35, transformer 44 to wire 37.
- 10 The relative direction of currents through transformer 44 is such that oscillations once started in the resonant circuit a^2 are maintained; that is, an increase in current in the direct current circuit will induce current in 15 the resonant circuit a^2 which will cause a change in the potential difference between the grid and filament which will tend to limit the flow of current in the direct current circuit through R^3 . The resulting decrease in the current of the direct current 20 circuit will induce an opposite impulse in the resonant circuit a^2 which will tend to increase the current in the D. C. circuit through R^3 , resulting in sustained oscillations of a frequency determined by the 25 constants of the circuits. Across the terminals of the primary of transformer 44 is connected a resonant circuit comprising condenser 46 and primary of transformer 45.
- 30 The variation in potential across primary of transformer 44 will thus induce oscillations in the circuit of transformer 45, whose secondary is connected in a tuned circuit through condenser 47 to the track rails H 35 and H' . It will be evident, therefore, that the low frequency alternating current in the transmission line 3^b is transformed into high frequency current by means of the hereinbefore described apparatus, and that 40 the said current may be utilized in the track rails for controlling signals as described in Figs. 1 and 4.

The signaling system shown in Fig. 7 is similar to that shown in Fig. 4 in that identical means is employed for impressing the 45 signaling currents upon the rails of each block section and that both frequencies of the signaling currents are obtained in each block section by bridging the insulated joints 2 of each section; but in this embodiment of my invention each bond M and M^a 50 comprises a wire 48, an impedance coil 49, and a condenser 50 which are arranged in series, the terminals of the wire being connected to the rails of the two adjacent block 55 sections upon opposite sides of the joints 2.

Each bond M and M^a is resonant to the frequency of the current which is directly supplied to the forward of the two sections 60 as in the form shown in Fig. 4, whereby the current which normally is directly supplied to each section is freely transmitted to the section next in the rear, but cannot reach the second section in the rear because it is 65 intercepted by a bond M which offers a rela-

tively high impedance to current of that frequency.

It will be noted that the system disclosed in Fig. 7 is without the roadside signals shown in Figs. 1 and 4, the purpose of which 70 is to avoid complexity of description, although I wish it to be clearly understood that the roadside signal may be used equally as well with this system as with the other systems.

75 The signaling device on the vehicle V of Fig. 7 is similar to that shown in Figs. 1 and 4, except that in lieu of amplifying the current for each of the relays P and P' by a single amplifier K connected to the coil 14, 80 the currents of each frequency are amplified independently of each other from the current in coil 14. This is accomplished by connecting to the terminals of the coil 14 a circuit including the wires 21 and 22 in 85 series with which is a condenser 15 and the primaries 51 and 51^a of a pair of transformers J and J' the whole forming a circuit a tuned broadly to the mean of the two frequencies of the generators 4 and 4^a. 90

The secondaries 52 and 52^a are identically electrically connected to the amplifiers K and K' respectively for amplifying the current transmitted to the relays P and P' , and it is, therefore, thought that an explanation of one will suffice for the other. 95

The apparatus for amplifying the current for relay P consists of a device K comprising a vacuum tube or bulb 16 having mounted therein a filament 17, a plate 19, and a 100 grid 18 interposed between the filament and the plate. The filament 17 is constantly heated by a battery 20 to which is connected one terminal of the secondary 52 of transformer J and a condenser 53 which is connected across the terminals of the secondary 52, the remaining terminal of secondary 52 being connected to the grid 18. A battery 23 is connected with the filament 17 and the plate 19 in such direction that a flow of current through the tube or bulb will result, owing to the electron emission from the heated filament 17. The oscillating difference in potential between grid 18 and the filament 17 serves to increase and decrease 110 the rate of emission of electrons from the filament and hence produces corresponding variations in the strength of current flowing in the circuit of battery 23. The circuit of battery 23 includes the primary of a 115 transformer 25, across the terminals of which is connected a condenser 24 to tune the transformer circuit to the frequency of its respective generator 4. The secondary of this transformer is connected with relay P by 120 means of a circuit made resonant by the condenser 26. Thus it will be seen that the variations in the strength of the current from battery 23 are reproduced as alternations in the resonant relay circuit. 125

It will be manifest from the preceding description that in operation the coil 14 being in inductive relation to the rails, which are charged with the two signaling frequencies of the generators 4 and 4^a, the frequencies will be reproduced in the coil 14 and transmitted to the transformers of the circuit α . The secondary circuits of these transformers each being resonant to one of the two frequencies will select its respective frequency and convey the same through the apparatus to their respective relays P and P' to energize the latter for controlling the signals G', Y' and R'.

15 So far as the action of the track circuits under various traffic conditions, is concerned the operation is identical with that previously described of Fig. 4; therefore, it is thought that a description of the same is unnecessary.

While I have stated in the foregoing specification that the frequencies of the signaling currents in the track rails should be "high", it will be clear that the effect of varying the frequency is an effect of degree only, in that the main purpose of these currents is to induce voltages in the train-carried receiving circuits and the higher the frequency the higher is the induced voltage for a given current value. So far as concerns the practical embodiments of my invention, then, the frequencies of the signaling currents are immaterial, the only requirement being that for reasonable values of currents in the track rails the voltages induced in the train-carried circuits shall be sufficient to reliably control the train governing apparatus. The word "high", therefore, as applied to these frequencies, is used solely with respect to the induction of sufficient voltage, and any frequency is high which accomplishes this.

It is thought from the foregoing, taken in connection with the accompanying drawings, that the construction and operation of my devices and their modifications will be understood by those skilled in the art and that minor changes of construction and arrangement of circuits may be made without departing from the spirit and scope of the appended claims.

Having thus described my invention, what I claim is:

1. A railway signaling system comprising track rails divided into block sections, means for impressing on the rails of each section signaling currents differing in frequency, a relay for each section receiving energy from the rails thereof and responsive to signaling current of one of said frequencies for controlling the supply of current of the other frequency to the section in the rear, a railway vehicle, and signaling means on said vehicle controlled by energy received from the track rails and selectively respon-

sive to currents of said frequencies to give a plurality of indications.

2. A railway signaling system comprising track rails divided into block sections, means for impressing on the rails of each section 70 signaling currents differing in frequency, means for each section controlled by traffic conditions therein for governing the supply of signaling current of one frequency to the rails of the section in the rear, a railway vehicle, and signaling means on said vehicle controlled by energy received from the track rails and selectively responsive to currents of said frequencies to give a plurality of indications.

3. A railway signaling system comprising track rails, a source of high frequency oscillating signaling current, a circuit resonant to said current and connected with said track rails, a railway vehicle, a circuit 85 thereon arranged to receive energy from said track rails, a second circuit on the vehicle resonant to said current, amplifying means interposed between said vehicle-carried circuits, and vehicle-governing 90 means controlled by said second vehicle-carried circuit.

4. A railway signaling system comprising a source of low frequency alternating current, transmission mains connected with said source and extending along the railway, means located at intervals along the railway for transforming said current into high frequency oscillating current, means for impressing said latter current on the track rails, 100 and signaling means controlled by the presence of said latter currents in the rails.

5. A railway control system embodying a plurality of means for producing across the rails periodic currents of respectively 105 different frequencies, train carried devices responsive respectively to said different periodic currents, a stop device held ineffective by one of said currents, and a speed control means rendered effective to produce a given speed by another current.

6. In a railway signaling system, in combination: a railway track; means nullified by the presence of a train on a predetermined portion of the track for normally supplying periodic signaling current to the track rails of the track for a predetermined distance in the rear; a vehicle adapted to travel over the track; a circuit on the vehicle resonant at the frequency of said signaling current and having a portion thereof disposed in inductive relation to the track rails; a relay on the vehicle responsive only to current of the frequency of said signaling current; and traffic protecting means on the vehicle governed by said relay.

7. Railway traffic controlling apparatus comprising track rails divided into block sections by insulated joints, means for each section controlled by traffic conditions in ad-

vance for impressing on the track rails thereof signaling currents of two different frequencies, a vehicle for travel on said rails, and means on said vehicle controlled by signaling currents in the track rails, and responsive to the presence of current of one of said frequencies only to give a caution indication, and to the presence of currents of both of said frequencies to give 10 a proceed indication.

8. A railway signaling system comprising track rails, means for impressing thereon high frequency oscillating signaling currents of two frequencies, two circuits controlled by energy in said rails and resonant respectively to said two frequencies, and signaling means controlled by said circuits.

9. Railway traffic controlling apparatus comprising track rails, a source of alternating signaling current connected thereto, a railway vehicle provided with an electron tube amplifier having a heated filament and a grid and a plate, a circuit on said vehicle inductively related to a track rail and including a capacity device, a grid circuit for said amplifier shunted by said capacity device, a plate circuit for said amplifier including a source of direct current, and means associated with said plate circuit and responsive to variations in the strength of the current flowing therein for governing said vehicle.

10. Railway traffic controlling apparatus comprising track rails, means for supplying alternating signaling current to said rails, a vehicle, a circuit on said vehicle including a winding in inductive relation with a track rail and a capacity device, an electron tube amplifier on said vehicle having its grid and filament connected across said capacity device, a plate circuit for said amplifier including a source of direct current, and means associated with said plate circuit and responsive to variations in the strength of the current flowing therein for governing said vehicle.

11. Railway traffic controlling apparatus comprising track rails, means for impressing two alternating signaling currents thereon, a vehicle provided with means for inductively receiving voltages due to said currents, and speed governing apparatus on said vehicle controlled by said voltages for permitting high speed when both currents are present in the track rails, an intermediate speed when only one current is present, and a low speed when both currents are absent.

12. Railway traffic controlling apparatus comprising a trackway divided into sections, means for constantly impressing an alternating signaling current on the rails of each section, means for each section controlled by traffic conditions in advance for impressing on the rails thereof a second alternating sig-

naling current, a vehicle provided with means for inductively receiving voltages due to said currents in the track rails, and apparatus on said vehicle controlled by said voltages for automatically governing the speed 70 of the vehicle.

13. Railway traffic controlling apparatus comprising track rails, means for impressing two alternating signaling currents thereon, a vehicle provided with means for inductively receiving voltages due to said currents, amplifying means on said vehicle controlled by the voltages impressed on said receiving means, and speed governing apparatus on said vehicle controlled by said amplifying means for permitting high speed 75 when both currents are present in the track rails, an intermediate speed when only one current is present, and a low speed when both currents are absent.

14. Railway traffic controlling apparatus comprising a trackway divided into sections, means for constantly impressing an alternating signaling current on the rails of each section, means for each section controlled by traffic conditions in advance for impressing on the rails thereof a second alternating signaling current, a vehicle provided with means for inductively receiving voltages due to said currents in the track 80 rails, amplifying means on said vehicle controlled by the voltage impressed on said receiving means, and speed governing apparatus on said vehicle controlled by said amplifying means.

15. Railway traffic controlling apparatus comprising a trackway divided into block sections, a vehicle for travel thereon, a circuit on the vehicle, means located in the trackway for creating an alternating potential in said circuit, a second circuit on the vehicle including a source of direct current, amplifying means on the vehicle controlled by the alternating potential in the first circuit for causing variations in the 95 strength of the current in said second circuit, a transformer whose primary is supplied with current from said circuit, a relay responsive to alternating current having a winding supplied with current from the secondary of said transformer, and vehicle governing means controlled by said relay.

16. Railway traffic controlling apparatus comprising a trackway, a vehicle for travel thereon, a circuit on the vehicle including a condenser, means located in the trackway for creating alternating signaling current in said circuit; an electron tube amplifier on said vehicle comprising a heated filament, a plate and a grid; the terminals of said condenser being connected with said filament and said grid respectively, a plate circuit for said amplifier, and vehicle governing means controlled by the current in said plate circuit.

17. Railway traffic controlling apparatus comprising track rails, a source of alternating signaling current connected thereto, a railway vehicle provided with a receiving circuit inductively related to a track rail and including a condenser, an amplifier on the vehicle having an input circuit connected across the terminals of said condenser, and vehicle governing means controlled by the 10 output circuit of said amplifier.

18. Railway traffic controlling apparatus comprising track rails, a source of alternating signaling current connected thereto, a railway vehicle provided with a receiving circuit inductively related to a track rail and including a capacity device, an amplifier on the vehicle having an input circuit shunted by said capacity device, and means controlled by the output circuit of said amplifier for 20 controlling the brakes of said vehicle.

19. Railway traffic controlling apparatus comprising track rails, a source of alternating signaling current connected thereto, a railway vehicle provided with a receiving circuit inductively related to a track rail and tuned by a condenser, and governing means on the vehicle controlled by the alternating difference of potential across said condenser.

20. Railway traffic controlling apparatus comprising track rails, a source of alternating signaling current connected thereto, a railway vehicle provided with a receiving circuit inductively related to a track rail and tuned by a capacity device, an amplifier on the vehicle having an input circuit shunted by said capacity device, and governing means on the vehicle controlled by the output circuit of said amplifier.

21. Railway traffic controlling apparatus comprising track rails, a source of alternating signaling current connected thereto, a railway vehicle provided with a receiving circuit inductively related to a track rail and tuned by a capacity device, an electron tube amplifier on said vehicle, a grid circuit for said amplifier shunted by said capacity device, a plate circuit for said amplifier, and governing means for said vehicle controlled by said plate circuit.

22. Railway traffic controlling apparatus comprising track rails, means for impressing an alternating signaling current thereon, a railway vehicle provided with a receiving circuit inductively related to a track rail and including a capacity device, and governing apparatus on said vehicle shunted by said capacity device.

23. Railway traffic controlling apparatus comprising a trackway, a vehicle for travel thereon, a circuit on said vehicle including a capacity device, means located in the trackway for creating alternating signaling current in said circuit, and governing apparatus on said vehicle shunted by said capacity device.

24. Railway traffic controlling apparatus comprising a trackway, a vehicle for travel thereon, a circuit on the vehicle including a condenser, means located in the trackway for creating alternating signaling current in 70 said circuit; and vehicle governing means controlled by the alternating difference of potential across said condenser.

25. Railway traffic controlling apparatus comprising a trackway and a vehicle for 75 travel thereon, a tuned circuit on said vehicle including a condenser, means located in the trackway for creating alternating signaling current in said circuit, and vehicle governing means of said vehicle controlled 80 by the alternating difference of potential across said condenser due to said signaling current.

26. Railway traffic controlling apparatus comprising track rails divided into block sections, a vehicle for travel thereon, means for each section for constantly impressing signaling current of one frequency on the rails thereof, means for each section controlled by traffic conditions in advance for impressing 85 signaling current of another frequency on the rails of the section, and means on said vehicle controlled by signaling currents in the track rails and responsive to the presence of current of the first-mentioned frequency 90 only to give a caution indication and to the presence of currents of both of said frequencies to give a proceed indication.

27. Railway traffic controlling apparatus comprising a trackway and a vehicle for 100 travel thereon, a receiving circuit on the vehicle, means in the trackway for creating alternating potentials differing in frequency in said circuit, a second circuit on said vehicle including a source of direct current, 105 an amplifying device controlled by the composite alternating potential in said receiving circuit for causing similar composite variations in the strength of the current in said second circuit, a third circuit and a 110 fourth circuit on said vehicle receiving current from said second circuit and tuned to resonance respectively at the frequencies of the two potentials created in said receiving circuit, and vehicle governing means controlled by currents in said third and fourth circuits.

28. Railway traffic controlling apparatus comprising track rails and a vehicle for travel thereon, means for impressing on said 120 track rails two alternating signaling currents differing in frequency, a receiving circuit on said vehicle in which is created a composite alternating potential due to said alternating currents in the rails, a second circuit on said vehicle including a source of direct current, an amplifying device controlled by the composite alternating potential in said receiving circuit for causing 125 similar composite variations in the strength 130 of

of the current in said second circuit, means on the vehicle for selectively disassociating the two components of the current variations in said second circuit corresponding in frequency to the two signaling currents in the track rails, and vehicle governing means controlled by said two component currents.

29. Railway traffic controlling apparatus comprising track rails and a vehicle for travel thereon, means for impressing on said track rails two alternating signaling currents differing in frequency, a receiving circuit on said vehicle in which is created a composite alternating potential due to said 15 alternating currents in the rails, a second circuit on said vehicle including a source of direct current, an amplifying device controlled by the composite alternating potential in said receiving circuit for causing similar 20 composite variations in the strength of the current in said second circuit, two transformers on said vehicle the primary of each transformer being included in said second circuit, secondary circuits for said transformers tuned to resonance at the frequencies 25 of said two signaling currents respectively, and vehicle governing means controlled by the currents in said secondary circuits.

30. Railway traffic controlling apparatus comprising track rails and a vehicle for travel thereon, means for impressing on said track rails two alternating signaling currents differing in frequency, a receiving circuit on said vehicle in which is created 35 a composite alternating potential due to said signaling currents in the rails; an electron tube on said vehicle comprising a heated filament, a plate and a grid; said filament and said grid being connected with 40 said receiving circuit, a plate circuit for said tube including a source of direct current, whereby the composite alternating potential in said receiving circuit causes similar composite variations in the current 45 strength in said plate circuit, means on the vehicle for selectively dissociating the two components of the current variations in said plate circuit corresponding in frequency to the two signaling currents in the track rails, 50 and vehicle governing means controlled by said two component currents.

31. In combination, a railway track divided into blocks, means associated with the track rails of each block and controlled 55 by traffic conditions in advance for transmitting proceed and caution indications from the track rails to a vehicle by induction, and means on the vehicle controlled jointly by said indications and by the speed of the vehicle for governing the vehicle brakes.

32. In combination, a railway track divided into blocks, means associated with the track rails of each block and controlled by traffic conditions in advance for trans-

mitting proceed and caution indications from the track rails to a vehicle by induction, and means on the vehicle controlled by said indications and by the absence thereof for imposing different fixed speed limits on 70 the vehicle.

33. In combination, a railway track divided into blocks, means associated with the track rails of each block and controlled by traffic conditions in advance for transmitting proceed and caution indications from the track rails to a vehicle by induction, and means on the vehicle responding to the caution indication by applying the brakes if the speed is above a given value, 75 and to the absence of both indications by applying the brakes if the speed is above a second and lower value.

34. Railway traffic controlling apparatus comprising a stretch of track divided into 80 successive track sections, line wires along said stretch supplied with energy, and means including an electron tube for each section supplied with energy from said line wires for supplying energy to the rails of 85 the associated section.

35. Railway traffic controlling apparatus comprising a stretch of track divided into successive track sections, line wires along 90 said stretch supplied with energy, and an electron tube for each section connected with said line wires for supplying energy to the associated section.

36. Railway traffic controlling apparatus comprising a stretch of track divided into successive track sections, line wires along 95 said stretch supplied with energy, an electron tube for each section, means for supplying the grid of each such tube with periodic energy from certain of said line wires, and means controlled by each tube for supplying 100 high frequency energy to the associated section.

37. In combination, a railway track divided into sections, a local generator of 110 alternating current for each section, and means including line wires extending along said track for energizing all of said generators from a common point.

38. In combination, a railway track 115 divided into sections, a local electron tube generator of alternating current for each section, and means including line wires extending along said track for energizing all of said generators from a common point.

39. In combination, a railway track divided into sections, a local electron tube generator of alternating current for each section, and means including line wires extending along said track for supplying the 125 filaments and plate circuits of said tubes from a common point.

40. The method of governing railway traffic which consists in producing in the track rails a flow of periodic current, and 130

governing the movement of a vehicle jointly by a centrifuge responsive to its speed variations and by said current in the track rails.

41. A railway traffic controlling system comprising traffic controlling apparatus carried on a railway vehicle and arranged to govern its movement and selectively responsive to currents of different frequencies

in the track rails, and means for supplying the track rails with currents of said different frequencies at respective successive points without superposing current of wrong frequency at any given point. 10

In testimony whereof I affix my signature.

LLOYD V. LEWIS.
